United States Patent

Des. 234,530
Patented Mar. 18, 1975

234,530

PLANTER

Simon V. Waitzman, Brooklyn, N.Y., assignor to Colonial Mirror and Glass Corporation

Filed May 9, 1973, Ser. No. 358,716

Term of patent 14 years

Int. Cl. D11—02

U.S. Cl. D35—3 A

FIG. 1

FIG. 2

FIG. 3

FIG. 1 is a view in perspective of a planter showing my new design;

FIG. 2 is a side elevational view thereof; and

FIG. 3 is a top plan view thereof.

I claim:

The ornamental design for a planter, substantially as shown.
